(57) **CLAIM**

The ornamental design for vision apparatus comprising eyewear frame and demountable display, as shown and described.

DESCRIPTION

FIG. 1 is a front perspective view of a vision apparatus comprising an eyewear frame and demountable display; FIG. 2 is a right side perspective view of the vision apparatus of FIG. 1 comprising an eyewear frame and demountable display;

FIG. 3 is a left side perspective view of the vision apparatus of FIG. 1 comprising an eyewear frame and demountable display;

FIG. 4 is a plan perspective view of the vision apparatus of FIG. 1 comprising an eyewear frame and demountable display;

FIG. 5 is a front perspective view of the demountable display of the vision apparatus comprising an eyewear frame and demountable display of FIG. 1;

FIG. 6 is a right side perspective view of the demountable display of the vision apparatus comprising an eyewear frame and demountable display of FIG. 1;

FIG. 7 is a left side perspective view of the demountable display of the vision apparatus of FIG. 1;

FIG. 8 is a plan perspective view of the demountable display of the vision apparatus comprising an eyewear frame and demountable display of FIG. 1;

FIG. 9 is a front perspective view of the eyewear frame of the vision apparatus comprising an eyewear frame and demountable display of FIG. 1;

FIG. 10 is a right side perspective view of the eyewear frame of the vision apparatus comprising an eyewear frame and demountable display of FIG. 1;

FIG. 11 is a left side perspective view of the eyewear frame of the vision apparatus comprising an eyewear frame and demountable display of FIG. 1; and,

FIG. 12 is a plan perspective view of the eyewear frame of the vision apparatus comprising an eyewear frame and demountable display of FIG. 1.

The broken lines depict unclaimed parts of the vision apparatus, and thus form no part of the claimed design.
